UNITED STATES PATENT OFFICE.

WILLIAM RILEY McKEEN, JR., OF OMAHA, NEBRASKA, ASSIGNOR, BY MESNE ASSIGNMENTS, TO McKEEN MOTOR CAR COMPANY, OF OMAHA, NEBRASKA, A CORPORATION OF NEW JERSEY.

SAFETY DEVICE.

1,052,938.

Specification of Letters Patent. Patented Feb. 11, 1913.

Application filed May 25, 1907. Serial No. 375,651.

To all whom it may concern:

Be it known that I, WILLIAM R. McKEEN, Jr., residing at Omaha, in the county of Douglas and State of Nebraska, have invented certain new and useful Improvements in Safety Devices, of which the following is a full, clear, and exact description, such as will enable others skilled in the art to which it appertains to make and use the same.

10 This invention relates to safety devices.

One of the objects thereof is to provide practical and effective means for minimizing danger in the storing and handling of explosive fluids.

15 Another object is to provide simple and efficient means for permitting the filling of a storage tank with an explosive fluid.

Another object is to provide means of the above character for permitting the safe and 20 ready discharge of the fluid from the tank.

Another object is to provide means of simple, durable and reliable construction adapted to permit the efficient filling of a tank with an explosive fluid and ready discharge thereof, and adapted, in the event of 25 a severe shock to or distortion of the tank, to prevent escape of its contents.

Other objects will be in part obvious and in part pointed out hereinafter.

30 The invention accordingly consists in the features of construction, combinations of elements and arrangement of parts which will be exemplified in the construction hereinafter set forth, and the scope of the application of which will be indicated in the following claims.

Referring now to the accompanying drawings, in which is shown one of the various possible embodiments of my invention, Figure 1 is a sectional elevation of a portion thereof; Fig. 2 is a detail end view of a cap with associated parts; Fig. 3 is a sectional view taken on the line *a—a* of Fig. 2; Fig. 4 is a top view of a plug and parts mounted therein; Fig. 5 is a bottom view of the same; Fig. 6 is a sectional elevation taken substantially on the line *b—b* of Fig. 4; Fig. 7 is a sectional view taken on the line *c—c* of Fig. 6; Fig. 8 is a similar view taken on the line *d—d* of Fig. 6; Fig. 9 is a view similar to Fig. 8 showing the parts in another position; Fig. 10 is a general diagrammatic view partially in section showing the parts assembled ready for use.

55 Similar reference characters refer to simi-

lar parts throughout the several views of the drawings.

In order that certain features of this invention may be the more readily and fully understood, it may here be noted that the handling of explosive fluids such as have come into somewhat general use for purposes of lighting and power is popularly supposed to be attended with more or less danger, and it is of a high degree of 60 commercial importance so to safeguard the handling and storage of this form of fuel as to do away with any possible chance of accidental explosion. The value of such safety devices is perhaps at a maximum in 65 cases in which cars or other vehicles are driven or lighted by the agency of hydro-carbon vapor, as whatever danger which may exist in the normal use of the apparatus is enhanced by the chance of derailment or 70 collision. The above and other advantageous features are attained in constructions of the nature of that hereinafter described.

Referring now to Fig. 10 of the accompanying drawings, there is shown a storage tank 1, which is imperforate save for the opening 2 in which is threaded a plug 3, hereinafter described more in detail. From this plug there leads a discharge conduit 4, to a carbureter 5, drawing from the lower 85 portion of the tank 1 through the tube 6. A filling or supply conduit 7 also leads to this plug and is shown mounted at its outer end in the car sheathing 8.

Turning now to Fig. 1 of the drawings, 90 in which the plug 3 is shown more in detail, it will be noted that there is formed therein a conical valve seat 9 seating a cock or valve 10 which is pressed against the seat by the spiral spring 11 held in position by a cap 12. This valve is provided with a port 13 and there is formed in the valve seat 9 a port 14 to permit the passage of fluid from the inner side of the valve to the interior of the tank. Valve 10 is rotated by a spindle 15 journaled in a bearing 16 formed in the elbow 17 and loosely fitting at its squared lower end 18 within a corresponding aperture formed in the valve. Upon the upper end of spindle 15 is mounted a crank arm 19, in which is pivoted a rod 20 having on its outer end a handle 21. These parts are so formed and related one to another that when the rod 20 is pulled 100 outwardly or away from the car-wall 8 the 110

passage is opened to the interior of the tank, whereas when the handle 21 is thrust home against the side of the car the valve 10 is closed. Elbow 17 is connected with the plug 3 by a section of piping 22 deeply grooved as indicated at 23, for a purpose hereinafter set forth. The other end of this elbow is connected with the supply conduit 7, which is tapped at its outer end into a flanged sleeve 24 bolted to the car sheathing and to the collar 25. The latter member is provided with inturned cam surfaces 26 which are adapted to be engaged by a pin 27 in a flanged cap 28 and when the latter is rotated, to force a gasket 29 against a seat 30 formed on sleeve 25 and thus close the opening to the conduit 7. The cap is then held in position by a spring-pressed locking pin 31. The outer flange of this cap, moreover, fits over the handle 21 and thus insures that the rod 20 will be thrust in and the valve 10 closed before the cap is placed in position. Also formed in plug 3 is a valve seat 32. The valve 33 co-acting therewith is normally forced in an upward direction by the spiral spring 34 resting against a bushing 35 tapped within the plug. The valve is normally held in an open position by rod or wire 36 soldered in an elbow 37, which is connected with the plug by the collar 38 and piping 39, the latter grooved as shown at 40. Elbow 37 is connected with the discharge conduit 4, as shown in Fig. 10 of the drawings, and there is tapped within the bushing 35 the tube 6 hereinbefore referred to.

Referring now to the plan view of the plug 3 given in Fig. 4, there is shown an air port 41 which leads to valve 10, as shown in Fig. 8. This port 41 is placed in connection with the interior of tank 1 by means of a port 42 and the passage 43 formed in the valve when the latter is rotated to bring the port 13 into registry with port 14. By this means, when the valve is turned into filling position, as shown in Fig. 9, there is provided free passage for the escape of air displaced by the entering fluid. There is also formed in plug 3 a valve seat 44, best shown in Fig. 6 of the drawings, which is normally closed by a valve 45. This valve is urged in a closing direction by a spring 46 which bears against cap 47. The passage beneath this valve is normally placed in connection with the interior of the tank 1 through the passage 43 and port 42, as shown in Fig. 8 of the drawings, and air is then admitted to the tank as the contents are withdrawn without the chance 60 of the stored fluid escaping through this opening.

The method of assembling the parts above set forth should be clear from the drawings, but it may be noted that valve or cock 10, after being thrust against its seat, is posi-

tively held in position by the end of a screw 48 resting within a slot 49 formed in the valve.

In order to do away with the chance of ambiguity in the interpretation of certain terms or expressions used throughout this case, it may here be noted that the term "tank" is employed to denote a receptacle of any kind, whatever its form or other characteristics, and that the expression "cock" is intended as a generic term to include a valve or closure of any form.

The operation of the above described embodiment of my invention is substantially as follows: When it is desired to fill the tank, the spring-pressed pin 31 is depressed and the cap 28 is turned to bring the ends of pin 27 through the recesses formed in the collar 25, whereupon the entire cap, with its gasket, may be withdrawn. The rod 20 is then drawn outwardly by the handle 21, rotating the spindle 15 and the valve or cock 10 to bring the port 13 into registry with port 14. Gasolene or any other desired fluid may then be poured into the tank 1 through the passage above described and the displaced air escapes through the port 42 and the passage 43 formed in the valve, passing outwardly through passage 41. The valve in this case is in the position shown in Fig. 9 of the drawings. After the tank has been filled to the desired extent, the handle 21 is thrust against its seat and the cap 28 is forced within the collar 25 and turned so as to wedge the ends of pin 27 beneath the cam surfaces 26, thus forcing gasket 29 against its seat. This series of operations results in the closing of port 13 and the connection of port 42 with valve 45 instead of with the passage 41, the valve being positioned as shown in Fig. 8 of the drawings. The flange of cap 28, moreover, locks handle 21 in the position immediately above described and prevents its withdrawal without first removing the cap.

Considering now the normal operation of the apparatus, the gasolene or other fluid may pass through the valve 33 to any desired destination, such as the carburetor 5, and air may enter the tank to take its place through the air check-valve 45 and port 42.

The purpose of the grooves 23 and 40 is to weaken the conduits 22 and 39 so that they may be readily broken in the event of unusual shock, such as might occur in the case of a collision. The breaking of the conduits 22 and 39 would release the entire tank, while the action of the valve 33 prevents the escape of its contents. The squared end 18 of the spindle 15 moves out of engagement with its seat in the valve 10, leaving that valve in its closed condition.

It is obvious that minor modifications might be made in the structure above set

forth, to accomplish the same general functions.

Having described my invention, what I claim as new and desire to secure by Letters Patent is:

5. 1. In a device of the class described, the combination of a tank; a supply conduit; and a connection between the supply conduit and the tank, the said connection having a mechanically weakened portion adapted to break when subjected to shock.
10. 2. The combination of a tank; a conduit adapted to conduct fluid connected to said tank; and a plurality of closures each adapted to close said conduit, the closures being arranged in interlocking relation whereby the closing of one is essential to the closing of another.
15. 3. In a device of the class described, in combination, a tank, a supply conduit, a normally closed cock controlling the passage to said tank, means having a frangible portion connecting said supply conduit with said cock, a closure for said supply conduit, and means controlling said cock and interlocking with said closure.
20. 4. In a device of the class described, in combination, a tank, a supply conduit, a normally closed cock controlling the passage to said tank, means having a frangible portion connecting said supply conduit with said cock, a closure for said supply conduit, and means controlling said cock and interlocking with said closure, said means being
25. 5. In a device of the class described, in combination, a tank, a supply conduit, a normally closed cock controlling the passage to said tank, means having a frangible portion connecting said supply conduit with said cock, a closure for said supply conduit, and means controlling said cock and interlocking with said closure, said means being detachably connected with said cock and adapted to permit the same to drop out of operative relation thereto.
30. 6. In a device of the class described, in combination, a tank, a supply conduit, a normally closed cock controlling the passage to said tank, a spindle controlling said cock and detachably connected therewith and adapted to permit the same to drop therefrom, means having a frangible portion connecting said supply conduit with said cock, a flanged cap adapted to close said supply conduit, and means adapted to be locked in position by the flange of said cap and controlling the position of said spindle.
35. 7. In a device of the class described, in combination, a tank, a supply conduit, a normally closed cock controlling the passage to said tank, means connecting said conduit with said cock having a mechanically weakened portion adapted to break upon being subjected to shock.
40. 8. In a device of the class described, in combination, a tank, a supply conduit, a normally closed cock controlling the passage to said tank, a spindle controlling said cock and detachably connected therewith and adapted to permit the same to drop therefrom, means having a frangible portion connecting said supply conduit with said cock, a flanged cap adapted to close said supply conduit, and means adapted to be locked in position by the flange of said cap and controlling the position of said spindle.
45. 9. In a device of the class described, in combination, a tank, a plug tapped within said tank, said tank being otherwise imperforate, a cock within said plug controlling the passage to said tank, a supply conduit, a closure for said conduit, and means controlling the position of said cock and interlocking with said closure.
50. 10. In a device of the class described, in combination, a tank, a spring-pressed valve controlling the passage leading therefrom, a discharge conduit leading from said valve and provided with a frangible portion, and means holding said valve open and positioned adjacent said conduit adapted upon said portion breaking to release and permit the closing of said valve.
55. 11. In a device of the class described, in combination, a tank, a spring-pressed valve mounted within said tank and adapted to close the passage leading therefrom, a conduit leading from said passage and provided with a frangible portion, and a rod secured within said conduit and normally holding said valve open, said rod being so arranged within said valve as upon said tank moving away from said conduit to permit the closure thereof.
60. 12. In a device of the class described, in combination, a tank, a plug secured in said tank, said tank being otherwise imperforate and said plug being formed with three ports leading into said tank and with an air passage, a supply conduit leading to said plug, a discharge conduit leading from said plug and a cock provided with a port adapted to register with one of said ports and connect said conduit with the interior of said tank and also provided with a passage adapted when said ports are in registry to connect said air passage with another of said first-mentioned ports.
65. 13. In a device of the class described, in combination, a tank, a plug secured within said tank, a supply conduit leading to said plug, said plug being provided with two ports leading to said tank, a check-valve formed within said plug and connected with the atmosphere, and a cock fitted within said plug and adapted in one position to open connection between said supply conduit and one of said ports and in another position to open connection between said check-valve and the other of said ports.
70. 14. In a device of the class described, in combination, a tank, a supply conduit, a cock controlling the passage to said tank, means connecting said supply conduit with said

- cock and provided with a frangible portion, and means adapted with said cock in open position to permit the exit of air from said tank and with the said cock in closed position to close said exit.
15. In a device of the class described, in combination, a tank, a supply conduit, a cock controlling the passage to said tank, means connecting said supply conduit with 10 said cock and provided with a frangible portion, means adapted with said cock in open position to permit the exit of air from said tank and with the said cock in closed condition to close said exit, a closure for 15 said supply conduit, and means controlling the position of said cock and interlocking with said closure.
16. In a device of the class described, in combination, a tank, a supply conduit, a discharge conduit, a cock controlling the passage from said supply conduit to said tank, a valve controlling the passage from said tank to said discharge conduit, frangible means connecting said supply conduit with 20 said cock and said discharge conduit with said valve, means adapted normally to maintain said cock in closed condition, and means adapted automatically to close said valve upon said frangible means breaking.
17. In a device of the class described, in combination, a tank, a plug secured within said tank, a normally closed cock controlling the passage leading within said tank, a valve within said plug controlling a passage leading from said tank, a discharge conduit connected with said valve, a supply conduit connected with said cock, a closure for said supply conduit, means controlling the position of said cock and interlocking with said closure, and means holding said valve open and adapted to release the same upon the tank becoming displaced.
18. In a device of the class described, in combination, a tank, a plug secured within said tank, a normally closed cock within said plug controlling the passage leading within said tank, a valve within said plug controlling a passage leading from said tank, a discharge conduit connected with said valve, a supply conduit connected with said cock, a closure for said supply conduit, means controlling the position of said cock and interlocking with said closure, and means holding said valve open and adapted to release the same upon the tank becoming displaced, said means connecting said conduits with said cock and said valve being provided with separable portions adapted to permit the displacement of said tank.
19. In a device of the class described, in combination, a tank, a plug secured within said tank, a normally closed cock within said plug controlling the passage leading within said tank, a valve within said plug controlling the passage leading from said tank, a discharge conduit connected with said valve, a supply conduit connected with said cock, a closure for said supply conduit, means controlling the position of said cock and interlocking with said closure, means holding said valve open and adapted to release the same upon the tank becoming displaced, and a check valve within said plug adapted to permit the entry of air within said tank.
20. In a device of the class described, in combination, a tank, a plug secured within said tank, a normally closed cock within said plug controlling the passage leading within said tank, a valve within said plug controlling a passage leading from said tank, a discharge conduit connected with said valve, a supply conduit connected with said cock, a closure for said supply conduit, means controlling the position of said cock and interlocking with said closure, means holding said valve open and adapted to release the same upon the tank becoming displaced, a check-valve within said plug adapted to permit the entry of air within said tank, and means adapted upon said cock being opened to permit the discharge of air from said tank.
21. In a device of the class described, in combination, a tank, a plug provided with passage secured within said tank, said tank being otherwise imperforate, a normally closed cock within said plug controlling the passage leading within said tank, a valve within said plug controlling a passage leading from said tank, a discharge conduit connected with said valve, a supply conduit connected with said cock, a closure for said supply conduit, means controlling the position of said cock and interlocking with said closure, means holding said valve open and adapted to release the same upon the tank becoming displaced, a check-valve within said plug adapted to permit the entry of air within said tank, and means adapted upon said cock being opened to permit the discharge of air from said tank.

In testimony whereof I affix my signature, in the presence of two witnesses.
